UNITED STATES PATENT OFFICE.

IRVING W. BEAN, OF BRAINTREE, MASSACHUSETTS.

DESIGN FOR A PERFUMERY BOTTLE.

Application filed September 5, 1928. Serial No. 28,054. Term of patent 3½ years.

To all whom it may concern:

Be it known that I, IRVING W. BEAN, a citizen of the United States, residing at Braintree, county of Norfolk, Commonwealth of Massachusetts, have invented a new, original, and ornamental Design for a Perfumery Bottle, of which the following is a specification, reference being had to the accompanying drawing, forming part thereof,

Fig. 1 is a face view of a perfumery bottle showing my new design, and
Fig. 2 is an edge view thereof.

I claim:

The ornamental design for a perfumery bottle, as shown.

IRVING W. BEAN.
